(57) **CLAIM**

The ornamental design for an electronic device case, as shown and described.

DESCRIPTION

FIG. 1 is a front isometric view of an electronic device case showing our new design;

FIG. 2 is a back isometric view thereof;

FIG. 3 is a right side view thereof;

FIG. 4 is a front view thereof;

FIG. 5 is a left side view thereof;

FIG. 6 is a top view thereof;

FIG. 7 is a bottom view thereof; and,

FIG. 8 is a back view thereof.

The broken lines in the drawing figures depict unclaimed subject matter only and form no part of the claimed design.
